UNITED STATES PATENT OFFICE.

JOHN SCHEMINGER, JR., OF PROVIDENCE, RHODE ISLAND.

COMPOSITE SPRAY-PLATE.

1,383,862.

Specification of Letters Patent.

Patented July 5, 1921.

Application filed December 8, 1919. Serial No. 343,342.

To all whom it may concern:

Be it known that I, JOHN SCHEMINGER, Jr., a citizen of the United States, residing at Providence, in the county of Providence and State of Rhode Island, have invented 5 certain new and useful Improvements in Composite Spray-Plates; and I do hereby declare the following to be a full, clear, and exact description of the invention, such as 10 will enable others skilled in the art to which it appertains to make and use the same.

This invention relates to atomizing devices for rotary oil or liquid fuel burners, and has for its object the production of a 15 rotary spray-plate or atomizing device possessing greater strength and better heat-resisting qualities than spray plates as ordinarily constructed, and by the use of which the atomization of oil or other liquid fuel 20 and the admixture thereof with air for supporting combustion may be effected in a more efficient manner and with more satisfactory results than is possible in using spray plates as heretofore ordinarily constructed.

The invention will first be hereinafter more particularly described, with reference to the accompanying drawings, which form a part of this specification, and then pointed 30 out in the claims at the end of the description.

In said drawings Figure 1 is a plan view of an atomizing device or spray-plate embodying my invention; and

Fig. 2 is a transverse section of the same. Referring to said drawings, in which the same reference letters are used to denote corresponding parts in different views, the letter A denotes the spray plate or atomizer, 35 which is designed to be mounted on the vertical shaft of a rotary oil burner, which is rapidly rotated in the usual manner by connection with a suitable motor for accomplishing the desired result. As shown, 40 the atomizing device consists of upper and lower metal plates or disks A' and A² having therebetween a sheet of asbestos or similar material B and having spaced openings C therethrough, preferably arranged 45 in circular series or rows between the center and circumference of the disk. Said openings are formed by slitting the metal plates at intervals and pressing the metal 50 plates upwardly on one side of the slit and downwardly on the other side thereof, so as to 55 form or provide oblong or oval-shaped open-

ings having their axes extending substantially in the plane of the plate or on approximately horizontal lines at an angle to the periphery of the plate in the manner set forth in my Patent No. 1,327,256, dated January 6, 1920, for atomizing devices for rotary oil burners, upon which my present invention is an improvement. The plates may be secured together with the asbestos sheet between my bolts or rivets ⁶⁰ a passing through holes in the two plates registering with holes in the interposed layer of asbestos, and the uppermost plate is bolted or riveted to a flange e projecting laterally from a hub-like portion or sleeve E, which is adapted to receive the vertical shaft to which the spray plate may be secured by a set screw entering a threaded aperture in said hub-like portion, which is fitted upon ⁶⁵ the shaft by a spline and groove connection to cause the same to rotate with the shaft while permitting adjustment lengthwise of the shaft. The letter F denotes inclined blades near the axis of the disk, which may be formed integrally with or secured to the flange e. The blades F are outwardly inclined, preferably tangentially to the axis of the disk, and at an angle to the axes of the oblong or oval openings through the ⁷⁰ disk. These blades serve to break up and whirl the oil or liquid fuel outwardly, for commingling with the air, which passes upwardly through the spray plate. The margin or periphery of the spray plate may be ⁷⁵ slit radially at intervals and the adjacent metal portions thereof bent upwardly and downwardly on opposite sides of the slits so as to form upwardly inclined vanes or ⁸⁰ vane-like portions or blades around the periphery of the plate, as shown.

A spray plate of the described construction, having a layer of asbestos or other heat-resisting material between two metallic plates, possesses better heat-resisting qualities than a single plate, is stronger, and is less liable to be warped when subjected to intense heat, and the life of the plate is much longer than that of a single plate, which easily warps and is not well adapted to withstand the intense heat to which such devices are subjected in oil burners of the class with which such spray plates are designed to be used.

In operation, as the spray plate is rapidly ¹¹⁰ rotated in the direction of the arrows in Fig. 1, the oil is thrown outwardly by the com-

bined action of the centrally disposed blades and the raised portions of the spray plate, together with commingled air onto the inclined peripheral blades and is further 5 broken up and atomized by the action of the last mentioned series of blades, and by reason of the peculiar form of the openings through the spray plate and the combined action of the inclined blades, a whirlwind 10 effect is produced, and a thorough atomization of the oil and commingling of the vapor with air is effected, for feeding the burner and maintaining a heating blaze thus producing more perfect combustion 15 with less waste of fuel than is usual in the operation of rotary oil burners.

While the spray plates are preferably formed or provided with the inclined blades at the circumference thereof, and also near 20 the center, or on opposite sides of the circular series of openings, one or both sets of blades may be omitted, and a greater or less number of rows of openings may be formed in the spray plate and various changes may 25 be made in the details and arrangement of parts without departing from the spirit and scope of my invention, and I therefore do not desire to be limited to the specific construction shown and described.

30 Having thus described my invention, what I claim as new and desire to secure by Letters Patent is:

1. A composite spray plate for rotary oil burners comprising a plurality of disks having 35 circular series of openings therethrough of oval shaped form arranged to effect the passage of fluid therethrough substantially in the plane of the disk, and a sheet of asbestos or similar reinforcing and heat-resist- 40 ing material between said disks having oblong openings therein which register with the openings through the disks.

2. A composite spray plate for rotary oil burners comprising a plurality of disks and 45 an interposed sheet of asbestos or similar reinforcing and heat-resisting material hav- 50 ing registering openings therethrough which are oblong in form and have their axes ex- tending on horizontal lines substantially in the plane of the plate.

3. A composite spray plate for rotary oil burners comprising a pair of dish-shaped metal plates each having slits formed therein and the metal raised or pressed upwardly on one side of the slit and depressed on the 55 other side thereof, so as to provide oval-shaped openings having their axes extending substantially in the plane of the plate; said raised and depressed portions being substantially concavo-convex and having their concave surfaces facing at the entrance to said openings and tapering as they recede therefrom and merging in the surface of the plate; said plates having a sheet of asbestos or similar reinforcing and heat-resisting mate- 60 rial placed therebetween and said sheet having openings therethrough which register with the openings in the plates.

4. A composite spray plate for rotary oil burners comprising a plurality of disks hav- 70 ing a sheet of asbestos or similar reinforcing and heat-resisting material therebetween, said disks and sheet having registering openings therein whose axes extend substantially in the plane of the plate; the upper plate 75 having thereon vertically disposed blades arranged at an angle to and encircling its axis, and the composite plate having a series of blades arranged at an angle thereto around its periphery.

5. An atomizing device for rotary oil burners consisting of a plurality of metal plates each slitted at intervals around its axis and having the metal upraised on one side of the slit and depressed on the other 85 side thereof so as to form openings having their axes extending substantially in the plane of the plate; said raised and depressed portions having concave surfaces facing at the mouth of said openings, and a sheet of asbestos or other reinforcing and heat-resisting material between said plates having openings 90 therein coincident with the openings in said plates.

In testimony whereof I affix my signature 95 in the presence of two witnesses.

JOHN SCHEMINGER, JR.
